G. G. CAMPANA

PERMANENT HAIR WAVING DEVICE

Original Filed Feb. 12, 1921

FIG. 1.

FIG. 2.

FIG. 3.

George G. Campana, INVENTOR.
Charles H. Wesson, BY ATTORNEY.

UNITED STATES PATENT OFFICE.

GEORGE G. CAMPANA, OF NEW YORK, N. Y., ASSIGNOR TO ERNEST O. FREDERICKS.

PERMANENT-HAIR-WAVING DEVICE.

Application filed February 12, 1921, Serial No. 444,338. Renewed August 1, 1922. Serial No. 579,063.

To all whom it may concern:

Be it known that I, GEORGE G. CAMPANA, a subject of the King of Italy, residing at New York, in the county and State of New York, have invented certain new and useful Improvements in a Permanent-Hair-Waving Device, of which the following is a specification.

This invention relates to devices for treating hair, and more particularly to a device for effecting what is known as a "permanent wave" upon hair upon the human head.

One of the objects of the invention is to provide a device wherein the permanent waving process may be carried on with a greater degree of safety, and with a less likelihood of injuring the hair than it has been possible to carry on the process in the use of devices as hitherto constructed.

Another object of the invention is to provide a device wherein all the hair being subjected to the permanent waving operation will be evenly treated, whereby the waves produced will be uniform.

A further object of the invention is to provide a device wherein the hair being treated may be conveniently observed during the permanent waving operation, whereby the existence of any condition which might lead to injury of the hair may be readily observed by the operator.

Another object of the invention is to provide a device combining a protective sheath for the hair together with a shield by means of which the scalp will be protected during the waving operation, the shield and the sheath having co-operating parts whereby they may be locked in position about a tress of hair.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claims.

In the accompanying drawing, wherein I have illustrated a preferred form of embodiment of my invention,

Figure 1 is a vertical sectional view taken through my improved device, showing the same positioned about a lock or tress of hair which is ready to be subjected to the permanent waving operation.

Figure 2 is a plan view of one part of my improved device; and

Figure 3 is an elevational view of a portion of another part thereof.

Referring now to the drawing, wherein similar reference characters refer to similar parts throughout the several views thereof, the reference numeral 1 illustrates a cylindrically formed tube, which is preferably formed of a heat refractory material, such, for instance, as glass, although, if desired, a refractory material such as mica may be employed. While it is desirable that the material employed for this purpose be transparent so that the interior thereof may be kept under the observation of the operator, the essential feature is that the material be refractory, and many other kinds of heat resistant material will be suitable for this purpose.

At its lower end, the tube 1 is provided with means by which a shield may be disposed thereon, the means here shown being oppositely located bayonet slots, one of which is clearly illustrated in Figure 3. The shield, to which reference has been made, is designated by the numeral 3 and this shield is to be interposed between the lower end of the tube 1 and the head or scalp of the person whose hair is being subjected to the waving operation. It will be understood, of course, that in the waving process, the locks of hair are twisted about a curler and, while maintained in this position, subjected to a heating process. The hair, while curled, is either moistened or else there is wrapped about it a moistened bandage in which various hair-treating substances are incorporated.

During the heating process, the heated vapors are likely to be given off and it is necessary to protect the scalp of the person being treated from such vapors. The shield which serves this purpose is here seen to be composed of three parts or wings, 4, 5 and 6, respectively, each of these parts or wings

2

being formed preferably of a heat resistant material. For this purpose I have found sheet fibre to be most useful, although other materials such as asbestos or other material 5 of that character could equally well be utilized. The parts or wings 4 and 6 are preferably kidney-shaped, as shown, and are pivoted together by a common means such, for instance, as the eyelet 7. This 10 construction permits the relative movement of each of the wings. Each of the parts or wings, 4, 5 and 6, is further provided on its inner edge with a slot or recess, these slots or recesses being, in turn, designated as 8, 15 9 and 10. Two of the wings 4 and 5 are, in turn, provided with upstanding semi-circular flanges 11 and 12, these flanges being disposed in opposed relation so that when the parts 4 and 5 are moved together, the 20 opposed edges of the flanges will come into engagement so as to provide a continuous circular flange rising vertically from the plane of the surfaces of the wings 4 and 5. The flanges 11 and 12 are further disposed 25 so that their contacting edges will come into engagement so as to form a substantially circular opening between the recesses 8, and 9, and this opening is adapted to accommodate the lock or tress of hair which is subjected to the permanent waving operation. 30

The flanges 11 and 12 are each provided with an inwardly extending post or projection, 13 and 14, these members being so disposed that when the flanges are in engagement to form a continuous circular flange, the posts will be so disposed as to be in position to enter the bayonet slots 2 provided at the lower end of the tube 1. The engagement of the slots with the projections or posts operates to hold the shield 35 firmly in position on the end of the tube and, further, serves the purpose of locking the wings or members 4 and 5 in the closed position; that is to say, with those parts of the shield in hair-engaging position.

Various other forms of connection could 40 be equally well used in this relation, the essential feature being that the shield is provided with upstanding members, by means of which a sliding connection is 45 made with the tube whereby the tube and the shield will be locked in relation relative to each other with the tube disposed in a position normal to the plane of the shield, the members of the shield further being 50 locked in engagement with the hair.

It will be noted that the opening 15, being provided by the closing together with the recesses 8 and 9 of the parts 4 and 5 of the 55 shield, will always be of uniform size inasmuch as the size thereof is limited or determined by the engagement of the flanges 60 11 and 12. It is desirable, however, that a substantially complete closure be effected 65 between the end of the tube 1 of the scalp, and this is effected by means of the part or wing 6 of the shield, which can be swung around to closely engage the hair, as shown in Figure 1, between the edge of the recess 10 and the edge of the recess 8.

The upper end of the tube 1 is fitted with a cap aperture 16, which fits closely upon the upper end of the tube, said cap being provided in a central location in its upper wall with an aperture 17 adapted to receive 70 the upper end of a curler 18, upon which the lock or tress of hair 19 has been wound. The curler 18 does not differ from the curlers for similar devices which are usually 75 used to carry out this process. It comprises 80 a small metal rod usually forked at its lower end, to which the lock or tress of hair near the scalp of the subject is tied as by means of a string or cord 19', a lock or tress being 85 thereafter tightly wound or twisted about 90 the curler and tied at its upper end as by means of the cord or string 20. The upper end of the curler is preferably left free so that the same may be projected through the aperture 17 of the cap 16. This aperture receiving the upper end of the curler, it will be noted, operates through the centre, the lock or tress of hair wound about the curler so that all parts thereof are 95 equidistant from the wall of the tube 1.

When all the parts together with the hair 100 have been assembled in the position shown in Figure 1 of the drawings, an electric heater having a circular bore is positioned upon the device so that the device may be subjected to the action of heat.

In carrying out the operation of permanent waving the hair upon the curler before it is inserted in the tube 1, is preferably 105 saturated or impregnated with a permanent waving substance, the material that is usually employed being a paste formed of borax, which paste is smeared over the surface of the hair upon the curler, so that 110 all the hair is saturated with borax or borax in solution. It will be understood, of course, that other materials may be used, if desired, in substitution of borax. When this has been done, the device is assembled in 115 a manner clearly indicated in Figure 1 of the drawings, whereupon it is ready to be subjected to the heat produced by the electric heater as aforesaid.

In the use of my device it will be seen 120 that from time to time the operator can slip off the electric heater, or move the same along the tube, whereby the hair upon the curler is always ready to be observed by the operator, thereby eliminating any danger of burning or scorching the hair. Moreover, in devices as hitherto constructed, the curler upon which the hair is curled or wound has been allowed to assume its own 125 position within the tube, that is to say, it was not centred with respect to the tube, so

that all the hair on the curler was not subjected to the same amount of heat. In my improved device, however, the hair upon the curler is centred in the tube, whereby each part of the curler is equi-distant from the heating surface of the electric heater positioned exteriorly of the tube. Moreover, the lower part of the tube is effectively closed by means of the shield construction, which shield not only forms a support for the tube, but which is adapted to be closed in such a way that there is no danger of steam escaping through the lower end of the tube, whereby the scalp of the person being treated may be scalped or burned during the permanent waving operation.

The fit between the upper end of the curler 18 and the aperture 17 of the cap 16, is, of course, such that the steam produced by the vaporization of the solution with which the hair is pregnant may readily escape through the aperture.

It will be seen that I have provided a protective device well adapted to attain the purposes and objects previously set forth, the main feature of which is to provide a protective shield which may be readily locked in hair-engaging position by a sliding connection with the tube, this connection serving the double purpose of locking the shield in operative position, both with relation to the hair and with relation to the tube in which the curler is disposed. The shield provides a tight fit about the lower end of the hair, thereby preventing the escape of steam, and protecting the scalp, while the means by which the shield is mounted on the tube insures that it will not be displaced during the waving process.

Obviously, other means could be used for the purpose of locking the shield in operative position about the lock of hair, but the method here illustrated is preferable inasmuch as it serves the double purpose above pointed out.

As many changes could be made in this construction without departing from the scope of the following claims, it is intended that all matter contained in the above description or shown in the accompanying drawing shall be interpreted as illustrative only and not in a limiting sense.

Having thus described my invention what I claim as new and desire to secure by Letters Patent is:

1. In a device of the class described, in combination, a tubular member, a shield having a plurality of parts adapted to be moved into engagement with a lock or tress of hair, said tubular member and said shield having mutually engaging interlocking parts.

2. In a device of the class described, a transparent tube adapted to be positioned about a tress of hair wound upon a curler, and means adapted to engage said tress

whereby to close the lower end of said tube, said means being interlocked with the lower end of said tube.

3. In a device of the class described, in combination, a transparent tube adapted to be positioned about a tress of hair wound about a curler, means adapted to engage said tress whereby to close the lower end of said tube, means to interlock said first-named means with the end of said tube and a cap fitted upon the opposite end of said tube.

4. In a device of the class described, in combination, a transparent tube, the lower end of which is slotted, a shield having a plurality of parts adapted to be moved into such position as to close the lower end of said tube about said tress of hair, said shield having means adapted to enter the slots of said tube, whereby the parts are locked together.

5. In a device of the class described, the combination of a transparent tube, adapted to receive a tress of hair wound upon a curler, a shield provided with a pair of pivotally mounted recessed parts, said parts being adapted to be swung toward each other so that the recesses thereof will form an opening to enclose said tress of hair near the base thereof, said parts being provided with upstanding flanges and locking means interposed between said flanges and the lower end of said tube.

6. In a device of the class described, the combination of a transparent tube, adapted to receive a tress of hair wound upon a curler, a shield provided with a pair of pivotally mounted recessed parts, said parts being adapted to be swung toward each other so that the recesses thereof will form an opening to enclose said tress of hair near the base thereof, said parts being provided with upstanding flanges and locking means interposed between said flanges and the lower end of said tube, and an apertured cap fitted upon the opposite end of said tube.

7. In a device of the class described, a cylindrical tube adapted to receive a lock or tress of hair wound upon a curler, a shield comprising a plurality of wings or parts pivotally connected together, all of said parts being provided with recessed edges, and two of said parts being provided with upstanding semi-circular flanges which, when said parts are swung toward each other, form an upstanding circular flange adapted to receive said tube, means upon said semi-circular flanges for engaging the lower end of said tube, whereby the parts are locked together, and another of said pivotally connected parts being adapted to be swung underneath said first mentioned parts, to modify or vary the size of the opening provided in the recesses of the edges of said first named parts.

8. In a device of the class described, a cylindrical tube adapted to receive a lock or tress of hair wound upon a curler, a shield comprising a plurality of wings or parts pivotally connected together, all of said parts being provided with recessed edges, and two of said parts being provided with upstanding semi-circular flanges which, when said parts are swung toward each other, form an upstanding circular flange adapted to receive said tube, means upon said semi-circular flanges for engaging the lower end of said tube, whereby the parts are locked together, and another of said pivot parts being adapted to be swung underneath said first mentioned parts, to modify or vary the size of the opening provided in the recesses of the edges of said first named parts, and an apertured cap positioned upon the opposite end of said tube adapted to receive the end of the curler. 9. As an article of manufacture, a shield for permanent waving device, comprising three parts or wings pivoted together at a common point, two of said wings having recesses in their inner edges co-operating when swung to operative position to define an aperture located centrally of said shield, and said third wing being adapted to be swung so as partially to close said aperture to provide an aperture located centrally of said shield. 10. In a device of the class described, a shield adapted to embrace a lock or tress of hair near the scalp, a cylindrical member adapted to receive a curler with a lock of hair wound thereon, and means mounted on the rim of said cylindrical member adjacent said shield for locking said cylindrical member to said shield. 11. In a device of the class described, a shield adapted to embrace a lock or tress of hair near the scalp, a cylindrical member adapted to receive a curler with a lock of hair wound thereon, and means mounted on the rim of said cylindrical member adjacent said shield for locking said cylindrical member to said shield, and a cap fitted upon the upper end of said tube provided in an aperture adapted to receive the free end of the curler. 12. In a device of the class described, a shield having a plurality of relatively movable parts adapted to engage a lock of hair, a cylindrical member adapted to receive a curler with a lock of hair wound thereon, and cooperating means on said cylindrical member and said shield to lock said shield in hair-engaging position. 13. In a device of the class described, a shield having a plurality of parts relatively movable to a position in engagement with a lock of hair, a tubular member, and means on said tubular member and said shield co-operable to retain the parts of said shield in hair-engaging position. 14. In a device of the class described, a tubular member, a shield comprising a plurality of relatively movable parts and means upon said shield engaging said tubular member and adapted to hold the latter in a position normal to the plane of said shield. 15. In a device of the class described, a tubular member, a shield comprising a plurality of relatively movable parts, said shield and said tubular member having inter-engaging parts adapted to hold the relatively movable parts of the shield in engagement with a lock or strand of hair. 16. In a device of the class described, a tubular member, a shield comprising a plurality of relatively movable parts, said shield and said tubular member being provided with co-operating means adapted to hold said shield in fixed position relative to said tubular member. 17. A device of the class described comprising, in combination, a tubular member and a shield adapted to restrict the opening in said member, said shield having upstanding parts adapted to embrace said tubular member, and said tubular member having means co-operating with said upstanding parts to hold said shield in restricting position. 18. A device of the class described comprising, in combination, a tubular member adapted to receive a curler with a lock of hair wound thereon, and a shield comprising a plurality of relatively movable parts, said shield having upstanding parts which embrace said member and said member having means co-operating with said upstanding parts to hold the movable parts of said shield in close engagement with a lock of hair. 19. A device of the class described comprising a tubular member adapted to receive a curler with a lock of hair wound thereon, and a shield comprising a plurality of relatively movable members, upstanding parts on two of said tubular members adapted to embrace said tubular members, and means on said tubular member co-operating with said upstanding parts to hold said movable members in close engagement with a lock of hair. In testimony whereof I affix my signature in the presence of two witnesses.

GEORGE G. CAMPANA.
